UNITED STATES PATENT OFFICE.

ALFRED C. DODGE, OF BINGHAMTON, NEW YORK.

COMPUTING-SCALE.

SPECIFICATION forming part of Letters Patent No. 760,432, dated May 24, 1904.

Application filed July 27, 1899. Serial No. 725,286. (No model.)

To all whom it may concern:

Be it known that I, ALFRED C. DODGE, a citizen of the United States, and a resident of Binghamton, in the county of Broome and 5 State of New York, have invented a new and useful Improvement in Computing-Scales, of which the following is a specification.

My invention relates to computing-scales.

It has for its object to simplify the construction of such scales, to dispense with the use 10 of removable weights or poises, to make such scales more sensitive, reliable, and accurate and less likely to get out of order, and generally to simplify the construction and operation 15 of such machines.

It consists in the novel devices herein shown and described.

In the drawings accompanying this specification and forming part hereof, and in which 20 similar reference characters in the different figures represent corresponding parts, I have shown and will now proceed to describe the preferred form or embodiment of my invention.

25 Figure 1 is a front view of a scale embodying my invention. Fig. 2 is a vertical section of the same, taken on the lines A A of Fig. 3, viewed as shown by the arrow; and Fig. 3 is a vertical cross-section taken on the lines B B 30 of Fig. 2 viewed as shown by the arrow. Fig. 4 is a plan of the supporting-levers. Fig. 5 is an enlarged detail face view of a part of one of the beams, showing the method of veneering the face of the beam with celluloid

35 and for marking the graduations thereon. Fig. 6 is a cross-section through the same on the lines A A of Fig. 5 viewed as shown by the arrow; and Fig. 7 is a detail showing the pound-and-ounce beam with my improved rev-40 oluble scoop-counterbalance weight attached thereto.

Referring now to the form or embodiment of my invention shown in the drawings, 1 and 45 2 form the combined dollar-and-cent beam; 3, the pound-and-ounce beam; 4, the steelyard-beam, and 5 the connecting-beam adapted to connect the steelyard-beam with the dollar-and-cent beam, as will be presently described.

6 is the cent-poise, and 7 the dollar-poise, 50 the said poises being adapted to slide along

the cent and dollar portions, respectively, of the dollar-and-cent beam.

8 is the pound-and-ounce poise adapted to slide along the pound-and-ounce beam 3.

9 is a supporting-poise mounted upon and 55 movable along steelyard-rod beam 4 and arranged to rest upon connecting-beam 5 at any point along the length of the said connecting-beam and to be supported by said connecting-beam. Steelyard-rod beam 4 is connected to 60 platform 38 and its connecting parts by means of the following-described mechanism: Movable platform 38 may rest upon supporting-levers in any well-known manner. As shown, these levers consist of a T-shaped lever 42 65 42 43 (the upper parts 42 42 of the T being connected to the steelyard-rods and the other end being preferably divided into two arms 46 46) and a lever 47. 48 48 are the pivots of these levers, upon which platform 38 rests, 70 and 49 49 are the pivots upon which the levers turn on the framework of the scale. Lever 47 runs under lever 43, as shown in Fig. 4, and is connected to lever 43 by loop 50 and pivot 51, integral with lever 43, and a similar 75 pivot 52, integral with lever 47. 42 is connected at each end by means of pivot 40 and loop 41 with steelyard-rods 32. These rods are secured at their upper ends to steelyard-rod beam 4. The weight of the load upon 80 platform 38 is thus borne through supporting-levers 47 46 43 42 and steelyard-rods 32, beam 4, supporting-poise 9, and connecting-beam 5.

The weight of the platform and its connections—namely, the supporting-levers, rods 32, beam 4, and poise 9—can be counterbalanced in any suitable manner. As shown, I accomplish it by means of a counter-lever 28, fulcrummed in any suitable manner to the framework of the scale and adapted to carry a weight 10 to counterbalance the platform and connections. As shown, I fulcrum lever 28 upon pivot 30, resting in a loop of counter-lever support 29, secured to the framework of 95 the scale. I pivotally connect the counter-lever 28 to the steelyard-rods. As shown, this is done by steelyard-rod support 34, secured to steelyard-rod 32, resting, by means of loop 35, on pivot 36, projecting from counter- 100

lever 28. Weight 10 is adjusted so as to exactly counterbalance the weight of the platform and its connections and, if desired, also any dish or receptacle that may be placed upon 5 the platform.

Connecting-beam 5 is fulcrumed in the framework of the scale at any suitable point. As shown in the drawings, it is fulcrumed at 10 24 in the casing by means of the usual pivot and loop. The dollar-and-cent beam is fulcrumed in the framework of the scale in any suitable manner. As shown, it is fulcrumed by means of two beam-stands 15, each having a cap 16, beam-stand bearing 17, and a pivot- 15 rod 18, engaging with the bearings and carrying the dollar-and-cent beam. The pivotal connections between the dollar-and-cent beam and the connecting-beam, as shown, consist of a connecting-rod 19, having an upper loop 20 and a lower loop 21, engaging with pivots 22 and 23 upon the dollar-and-cent beam and connecting-beam, respectively, as shown in Fig. 2. By shifting the supporting-poise 9 along steelyard-rod beam 4, so as to cause the 25 poise to rest upon connecting-beam 5 at different points, the weight of the load is carried by the connecting-beam at different points. By this shifting and by the moving of the sliding poises 6 and 7, or either one of them, 30 along the dollar-and-cent beam the proper amount of the load for a given amount of money and at a fixed price, or the value of the load at a given price, or the price of a given weight of load for a fixed amount of 35 money, can be readily and automatically computed by the machine.

Suitable graduated scales are arranged in connection with the dollar-and-cent beam, the connecting-beam, and the pound-and-ounce 40 beam, as shown in Fig. 1. The price-scale 26 is preferably placed upon the face of cap 25 of the machine. An indicator 27 is secured to poise 9, so as to move with it. This indicator passes forward through a slot in the cap 45 and is adapted to move over the face of the price-scale 26. Poise 9 can be moved along steelyard-rod beam 4 by any suitable means. In the form of device shown I move it by means of indicator 27. The pound-and-ounce 50 beam 3 is secured to counter-lever 28, so as to swing with it. By means of beam 3, poise 8, lever 28, gooseneck 31, and weight 10 the machine can be used for the simple weighing of articles. When used as a computing-scale, 55 however, poise 8 must be pushed to the extreme left, as shown in Fig. 1.

In order to bring steelyard-rod beam 4 and supporting-poise 9 above connecting-beam 5, which is the preferred form of construction, I preferably curve the rods 32 at 60 point 44, so as to form a half-loop around connecting-beam 5. In the form shown in the drawings I also preferably form a loop 33 in the said steelyard-rods in order to take 65 them around counter-lever 28.

I preferably make the dollar and cent poises so that the dollar-poise will be relatively many times heavier than the cent-poise. This, together with the form of my dollar-and-cent beam and its arrangement and connection with the other parts of the mechanism, enables me to entirely dispense with the use of removable weights in connection with that beam and to dispense with all weights in connection therewith except the 70 sliding poises. The construction of this part of my improved mechanism is thus greatly simplified and the inconvenience and danger attendant upon the use of movable parts are entirely obviated. 75

12 and 13 are two disks, each mounted upon an arm pivoted to the pound-and-ounce beam and made so that they can partially revolve. They are so arranged that one only of them is in sight at a time, the other being screened 80 by the beam. These disks and arms form a counterbalance-weight for neutralizing the weight of a scoop when placed upon platform 38. When the counterbalance is in the position shown in Fig. 7, the scoop is supposed 85 to be off. When the scoop is put on, the disks are turned a quarter-revolution to the right, bringing disk 13 in sight and screening disk 12. This slight shifting of the weight of the disk relative to the fulcrum neutralizes the 90 weight of the scoop. Suitable words or marks are placed upon the disks to indicate the absence or presence of the scoop. As shown, upon disk 12 the words "Put scoop 95 off" are used, and upon disk 13 the words 100 "Put scoop on" or equivalent expressions are preferably used.

11 11 are the indicating-needles usual in computing-scales, and 14 is the beam-stop.

39 is the base of the computing-scale, and 105 37 37 are the columns which support the cap.

I prefer to veneer the face of each scale-beam with celluloid or other similar substance, placing the scale-graduated marks upon such veneering. With a scale-beam 110 thus arranged the scale-graduated marks are much more distinct and legible than when made in the usual manner upon metal.

In Figs. 5 and 6 I have shown my preferred construction. As shown, 52 is the celluloid 115 veneering, and 53 53 represent the graduations placed upon the face of such veneering, preferably in intaglio, and 54 the metallic base of the scale-beam upon which the veneering is laid.

Heretofore in computing-scales it has been usual to shift the fulcrum. This, however, involves the use of a carriage or other complicated device to accomplish the shifting of the fulcrum, which seriously interferes with 125 the efficiency and practical use of such machines. It makes them complicated in structure, expensive in construction, difficult to use, and liable to disarrangement of the parts. In my improved device the fulcrum is always 130

stationary and the weight of the load is shifted relatively to the fulcrum and the weight of the poises. This I accomplish by means of the supporting-poise 9 and its connections.

5 By these means I am enabled to dispense with a carriage or complicated construction. The shifting of the weight of the load is easily and readily accomplished. No complicated mechanism is required, the entire construction of 10 the computing-scale is very much simplified, and the scale made much more sensitive, reliable, and accurate and less likely to get out of order. I am also enabled to dispense with removable weights in connection with the dollar-and-cent beam, as above described.

15 I am aware that attempts have been made heretofore to make a computing-scale in which the weight of the load is shifted; but in all such scales of which I am aware the weight of 20 the load is caused to operate the scale by a push upward instead of as in my construction by the pulling downward of the weight through a supporting-poise resting upon a connecting-beam. In the prior constructions 25 referred to a complicated and intricate system of supporting-levers is required and the entire construction is more complicated and less direct and efficient in its operation. Moreover, it has been found necessary in such constructions 30 to employ movable weights in connection with the dollar-and-cent beam. By means of my improvement the computing-scales are, moreover, made more sensitive and the removable weights referred to are entirely 35 dispensed with.

What I claim as new, and desire to secure by Letters Patent, is—

1. In a computing-scale the combination of 40 a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along 45 the steelyard-rod beam and adapted to engage with, press down upon and be supported by, the connecting-beam when a load is placed upon the platform, a dollar-and-cent beam fulcrumed in the framework of the scale, dollar 50 and cent poises mounted thereon, and pivotal connections between said beam and the connecting-beam, whereby by the shifting of the supporting-poise along the connecting-beam and the moving of the dollar and cent poises 55 or either of them along the dollar-and-cent beam, amount, value or price can be automatically computed.

2. In a computing-scale the combination of 60 a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along 65 the steelyard-rod beam and adapted

to engage with, press down upon and be supported by, the connecting-beam when a load is placed upon the platform, means for counter-balancing the said platform, supporting-levers, rods, beam and supporting-poise, a dollar-and-cent beam fulcrumed in the framework of the scale, dollar and cent poises mounted thereon, and pivotal connections between said beam and the connecting-beam, whereby by the shifting of the supporting-poise along the connecting-beam and the moving of the dollar and cent poises or either of them along the dollar-and-cent beam, amount, value or price can be automatically computed.

3. In a computing-scale the combination of 80 a movable platform, supporting-levers therefor, steelyard-rods connected with the said levers, curved at one place so as to form a half-loop around the connecting-beam, a steelyard-rod beam secured to the steelyard-rods, 85 a connecting-beam fulcrumed in the framework of the computing-scale and arranged below the steelyard-rod beam, a poise mounted upon and movable along the steelyard-rod beam and adapted to engage with, press down upon and be supported by, the connecting-beam when a load is placed upon the platform, a dollar-and-cent beam fulcrumed in the framework of the scale, dollar and cent poises 90 mounted thereon, and pivotal connections between said beam and the connecting-beam, whereby by the shifting of the supporting-poise along the connecting-beam and the moving of the dollar and cent poises or either of them along the dollar-and-cent beam, amount, 95 value or price can be automatically computed.

4. In a computing-scale the combination of 100 a movable platform, interconnected supporting-levers therefor, steelyard-rods connected to one of said levers, a steelyard-rod beam secured to the steelyard-rods, a connecting-beam fulcrumed in the framework of the scale, a poise mounted upon and movable along the steelyard-rod beam and adapted to engage with, press down upon and be supported by, the connecting-beam when a load is placed upon the platform, an indicator secured to and moving with the said poise, a price-scale over which the indicator is adapted to move, a dollar-and-cent beam fulcrumed in 105 the framework of the scale, dollar and cent poises mounted thereon, and pivotal connections between said beam and the connecting-beam, whereby by the shifting of the supporting-poise along the connecting-beam and 110 the moving of the dollar and cent poises or either of them along the dollar-and-cent beam, amount, value or price can be automatically computed.

5. In a computing-scale the combination of 115 a movable platform, interconnected supporting-levers therefor, steelyard-rods connected to one of said levers, a steelyard-rod beam secured to the steelyard-rods, a connecting-beam fulcrumed at one end in the framework of the 120

- computing-scale, a poise mounted upon and movable along the steelyard-rod beam and adapted to engage with, press down upon and be supported by, the connecting-beam
- 5 when a load is placed upon the platform, a dollar-and-cent beam fulcrumed in the framework of the scale, a poise mounted thereon upon one side of the fulcrum and a rod pivoted at one end to the said beam upon the opposite side of the fulcrum and pivoted at its other end to the connecting-beam between the fulcrum of the latter and the supporting-poise, whereby by the shifting of the supporting-poise along the connecting-beam and the moving of the poise along the dollar-and-cent beam, amount, value or price can be automatically computed.
6. In a computing-scale the combination of a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along the steelyard-rod beam and adapted to engage with, press down upon and be supported by, the connecting-beam when a load is placed upon the platform, a counter-lever fulcrumed to the framework of the scale and adapted to carry a weight to counterbalance the platform and connecting parts, pivotal connections between said counter-lever and the steelyard-rods to enable the counter-lever and weight to operate, a dollar-and-cent beam fulcrumed in the framework of the scale, dollar and cent poises mounted thereon, and pivotal connections between said beam and the connecting-beam, whereby by the shifting of the supporting-poise along the connecting-beam and the moving of the dollar and cent poises or either of them along the dollar-and-cent beam, amount, value or price can be automatically computed.
7. In a computing-scale the combination of a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along the steelyard-rod beam and adapted to engage with, press down upon and be supported by, the connecting-beam when a load is placed upon the platform, a dollar-and-cent beam fulcrumed near one of its ends in the framework of the scale, dollar and cent sliding poises mounted thereon, the dollar-poise being relatively many times heavier than the cent-poise, a rod pivoted at one end to the said beam upon the opposite side of the fulcrum from that of the poises and pivoted at its other end to the connecting-beam, whereby by the shifting of the supporting-poise along the connecting-beam and the moving of the dollar and cent poises or either of them along the dollar-and-cent beam, amount, value or price can be automatically computed without the use of other weights in connection with the dollar-and-cent beam than the said sliding poises.
8. In a computing-scale the combination of a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along the steelyard-rod beam and adapted to engage with, press down upon and be supported by, the connecting-beam when a load is placed upon the platform, means for counterbalancing the said platform and its connections, a dollar-and-cent beam fulcrumed near one of its ends in the framework of the scale, dollar and cent sliding poises mounted thereon, the dollar-poise being relatively many times heavier than the cent-poise, a rod pivoted at one end to the said beam upon the opposite side of the fulcrum from that of the poises and pivoted at its other end to the connecting-beam, whereby by the shifting of the supporting-poise along the connecting-beam and the moving of the dollar and cent poises or either of them along the dollar-and-cent beam, amount, value or price can be automatically computed without the use of other weights in connection with the dollar-and-cent beam than the said sliding poises.
9. In a computing-scale the combination of a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along the steelyard-rod beam and adapted to engage with, press down upon and be supported by, the connecting-beam when a load is placed upon the platform, a dollar-and-cent beam fulcrumed near one of its ends in the framework of the scale, dollar and cent sliding poises mounted thereon, the dollar-poise being relatively many times heavier than the cent-poise, a rod pivoted at one end to the said beam upon the opposite side of the fulcrum from that of the poises and pivoted at its other end to the connecting-beam, whereby by the shifting of the supporting-poise along the connecting-beam and the moving of the dollar and cent poises or either of them along the dollar-and-cent beam, amount, value or price can be automatically computed without the use of other weights in connection with the dollar-and-cent beam than the said sliding poises.
10. In a computing-scale, a revoluble scoop counterbalance-weight having two arms pivoted to a pound-and-ounce beam of the scale, each arm carrying a disk, one disk indicating the presence of the scoop and the other the absence of the same and means for screening

price can be automatically computed without the use of other weights in connection with the dollar-and-cent beam than the said sliding poises.

8. In a computing-scale the combination of a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along the steelyard-rod beam and adapted to engage with, press down upon and be supported by, the connecting-beam when a load is placed upon the platform, means for counterbalancing the said platform and its connections, a dollar-and-cent beam fulcrumed near one of its ends in the framework of the scale, dollar and cent sliding poises mounted thereon, the dollar-poise being relatively many times heavier than the cent-poise, a rod pivoted at one end to the said beam upon the opposite side of the fulcrum from that of the poises and pivoted at its other end to the connecting-beam, whereby by the shifting of the supporting-poise along the connecting-beam and the moving of the dollar and cent poises or either of them along the dollar-and-cent beam, amount, value or price can be automatically computed without the use of other weights in connection with the dollar-and-cent beam than the said sliding poises.

9. In a computing-scale the combination of a movable platform, interconnected supporting-levers therefor, steelyard-rods connected to one of said levers, a steelyard-rod beam secured to the steelyard-rods, a connecting-beam fulcrumed in the framework of the computing-scale, a poise mounted upon and movable along the steelyard-rod beam and adapted to engage with, press down upon and be supported by, the connecting-beam when a load is placed upon the platform, a dollar-and-cent beam fulcrumed near one of its ends in the framework of the scale, dollar and cent sliding poises mounted thereon, the dollar-poise being relatively many times heavier than the cent-poise, a rod pivoted at one end to the said beam upon the opposite side of the fulcrum from that of the poises and pivoted at its other end to the connecting-beam, whereby by the shifting of the supporting-poise along the connecting-beam and the moving of the dollar and cent poises or either of them along the dollar-and-cent beam, amount, value or price can be automatically computed without the use of other weights in connection with the dollar-and-cent beam than the said sliding poises.

10. In a computing-scale, a revoluble scoop counterbalance-weight having two arms pivoted to a pound-and-ounce beam of the scale, each arm carrying a disk, one disk indicating the presence of the scoop and the other the absence of the same and means for screening

125

130

one of the disks and exposing the other, whereby by the partial revolution of the counterbalance-weight the presence or absence of the scoop can be indicated and neutralized.

5 11. In a scale a revoluble scoop counterbalance-weight having two arms pivoted to a beam of the scale, each arm carrying a disk, one disk indicating the presence of the scoop and the other the absence of the same, and means
10 for screening one of the disks at a time and exposing the other, whereby by the partial

revolution of the counterbalance-weight the presence or absence of the scoop can be indicated and neutralized.

In testimony whereof I have signed my name ¹⁵ to this specification in the presence of two subscribing witnesses.

ALFRED C. DODGE.
